CLAIM

The ornamental design for an aiming reticle, as shown and described.

DESCRIPTION

FIG. 1 is a front elevational view of an aiming reticle; and, FIG. 2 is an enlarged detail view of the aiming reticle of FIG. 1.

The evenly broken lines in the drawings depict unclaimed portions of the aiming reticle. The dash-dot broken lines depict unclaimed boundary of the claimed design. The alternating long and short dash broken lines depict unclaimed boundary of the isolated view shown in FIG. 2. The broken lines form no part of the claimed design.
